ALBERT F. SAUNDERS, OF SYRACUSE, NEW YORK, ASSIGNOR TO T. N. BENEDICT MFG. CO., OF EAST SYRACUSE, NEW YORK.

DESIGN FOR A GOBLET.

52,995.

Specification for Design.

Patented Feb. 11, 1919.

Application filed November 14, 1918. Serial No. 262,610. Term of patent 7 years.

To all whom it may concern:

Be it known that I, ALBERT F. SAUNDERS, a citizen of the United States, residing at 106 Rugby road, city of Syracuse, county of Onondaga, and State of New York, have invented a new, original, and ornamental Design for a Goblet, of which the following is a specification, reference being had to the accompanying drawing, forming part thereof.

Figure 1 is a plan view of a goblet embodying my design.

Fig. 2 is an elevation thereof.

This design for a goblet comprises an elongated body in the general form of a parabola, and curving slightly outward toward the upper part of body forming a flared

edge or lip at the top. The body is supported upon an inverted dish shaped base or foot, by a connecting stem the general form of which is a hyperbola.

I claim:

The ornamental design for a goblet, substantially as shown and described.

In testimony whereof I have hereunto signed my name, at East Syracuse, in the county of Onondaga and State of New York, this 11th day of November, 1918.

ALBERT F. SAUNDERS.
